ROBERT H. WRIGHT AND MIDDLETON S. GILL, OF MEXICO, MISSOURI.

ROTARY ENGINE.

No. 880,614.

Specification of Letters Patent.

Patented March 3, 1908.

Application filed April 23, 1907. Serial No. 369,782.

To all whom it may concern:

Be it known that we, ROBERT H. WRIGHT and MIDDLETON S. GILL, citizens of the United States, and residents of Mexico, in 5 the county of Audrain and State of Missouri, have invented an Improved Rotary Engine, of which the following is a specification.

This invention is an improvement in rotary engines, and consists in certain novel 10 constructions and combinations of parts as will be hereinafter described and claimed.

In the drawings—Figure 1 is a vertical longitudinal section of an engine embodying our invention. Fig. 2 is a detail perspective view of a reversing worm wheel. Fig. 3 is a cross section of the engine on about line 3—3 of Fig. 1. Fig. 4 is a detail perspective view of one of the piston blades. Fig. 5 is a detail elevation of one of the cam 20 plates showing the cam groove therein for operating the abutments. Fig. 6 is a side view, and Fig. 7 a top plan view of one of the abutments, this figure showing also one of the slide rods. Fig. 8 is a detail section on about line 8—8 of Fig. 7. Fig. 9 is a sectional view, and Fig. 10 a perspective view of one of the valves. Fig. 11 is a section on about line 11—11 of Fig. 1, showing the transmission mechanism. Fig. 12 is a sectional view, and Fig. 13 a perspective view of one of the check valves for use in the relief passages. Fig. 14 is a sectional perspective view of a portion of one of the side sections of the casing. Fig. 15 is a detail perspective view of a portion of the ring for supporting the slide rods, and Fig. 16 is a detail sectional view illustrating the part in which certain of the pinions work as presently described. Fig. 17 is a detail section on about line 17—17 of Fig. 16, and Fig. 18 is a detail top plan view of the bearing projection shown in Figs. 1, 16 and 17.

In carrying out our invention, we provide a casing A, which is preferably made in sections, as illustrated in Fig. 1, abutting at A', and this casing A has the cylinder A² carrying the abutments B, and within which the piston C operates in the use of the invention. The casing A has a suitable base A³ which 45 may be bolted or otherwise secured to a suitable foundation, and the casing has the body portion A⁴ provided at A⁵ with bearings for the piston shaft, and has at its outer end a widened portion forming lateral offsets A⁶ 50 providing the recesses A⁷ within which the abutments B operate in the use of the inven-

tion. These offsets A⁶ also provide for the radial openings A⁸ in which the slide rods B' for operating the abutments B are movable radially, and these slide rods B' are provided near their inner ends with projections B⁹ operating in cam grooves E' in the cam plates E. These cam grooves E' have the outwardly extending portions E² corresponding in number and arrangement to the blades D' 60 of the piston C, and the cam plates E are keyed on the piston shaft F to which shaft the piston C is also secured, it may be by bolting at D² as shown, or otherwise as desired. The cam plates and the piston being 70 thus secured to the same shaft, are maintained in fixed relation, so that the abutments B will be moved out and in in correspondence with the piston blades D', as the latter pass the abutments in the operation of 75 the invention, as more fully described hereinafter. In connecting the slide rods B' with the abutments B, the latter are provided at their ends with projecting lugs B³ spaced apart, and the slide rods B' are grooved in 80 their opposite sides at B⁴—see Fig. 7—to fit between and engage with the said lugs B³, as will be understood from Figs. 1 and 6 of the drawings. This permits the ready application and removal of the parts in assembling 85 the engine.

In Fig. 15 we show a ring B¹⁰ having radial openings B¹¹ guiding the slide rods B'. The ring B¹⁰ fits between the sections of the cam plate, see Fig. 1, and is provided in its outer 90 edge with notches B¹² receiving lugs projecting inwardly from the rim of the case, whereby the guide ring will be held from rotating with the cam plates.

The piston C operates in a continuous circumferential slot A⁹ formed in the inner circumferential wall A¹⁰ of the casing, and at intervals corresponding to the number of piston blades D', the outer circumference of the wall A¹⁰ is recessed transversely at A¹¹ to 100 receive the abutments B, and the abutments B when closed against the piston, overlie the outer edge of the body of the piston C, and the outer surface of the inner circumferential portion A¹⁰ of the casing, and preferably 105 fit in shallow grooves in the outer surface of the circumferential portion A¹⁰, A¹¹, and are drawn down into such grooves by the action of the slide rods in the cam grooves E'. To secure a tight fit across the joint, between 110 the abutment B and the outer edge of the body of the piston C, the central portions B⁵

of the abutments are preferably slidably connected with the body portions of the abutments and actuated by a spring B^6 forming packing strips to pack the joint between the abutments and the outer circular edges of the body of the piston. These packing portions B^5 are limited in their movements by studs B^7 on the packing portions B^5 entering slots B^8 in the abutments, as will be understood from Figs. 6 and 8 of the drawings.

In the construction of casing as before described, it will be noticed the casing is made of two side sections having the outer side plates and the inwardly projecting flanges which on the opposite sections form the inner circumferential wall A^{10} before described and the outer wall or rim in which the recesses A^7 for the reception of the abutments B are formed as before described. It will be noticed that the inner flanges forming the inner circumferential wall A^{10} are not as long as the flanges forming the outer rim, thus affording the space or slot between them for the operation of the piston as shown in Fig. 1.

The piston C operates between the inner adjacent ends of the inner flanges of the side sections of the casing and is preferably circular in form, see Fig. 3, is packed by triangular rings C^{10} at its rim edges, and is provided with the blades D' of which we show two in the construction illustrated in Fig. 3. Manifestly, the number of these blades may be increased without departing from any of the principles of our invention. This piston is secured to the hollow shaft F which revolves with the piston and the shaft F at one side of the piston, communicates through a central opening C' with feed channels C^2 leading outwardly within the piston to the blades thereof and having feed ports C^3 opening in opposite directions to the steam space C^4 within the casing so that the steam may operate between the piston blade and the next abutment in rear thereof in the operation of the invention.

Our improved engine will be found especially useful in compounding, in doing which the primary and secondary engines, etc., may be constructed alike, except varying as to size, as is usual in compound engines, and the several engines of the series may be suitably geared, as will be understood by those skilled in the art. This special adaptation of the engine for compounding purposes, results largely from the relative arrangement and number of the abutments with respect to the piston blades, whereby the steam exhausted from one engine to the succeeding engine is taken from between closed abutments.

It will be noticed that we provide three abutments for each of the piston blades, and these abutments are so arranged that after one blade has passed any given abutment,

the steam space C^4 between such given abutment and the next one in rear, will be entirely unobstructed by any piston blade so that the steam in said space may exhaust freely to a succeeding engine in a compound arrangement of engines. In the operation of this construction, during about two-thirds of the travel of the exhaust port G from the rear toward the abutment in advance, the pressure of steam per square inch on the piston blade of the secondary engine will be much greater than the back pressure of the secondary engine upon the blade of the primary engine, this being one object in using the three abutments, a second object being to permit the raising and lowering of said abutments at a time when they are free from steam pressure and the friction resulting therefrom. This is an important feature of our invention, and in carrying it out, we provide exhaust channels G formed in the piston in rear of their respective blades and in such relation thereto that they will after the piston blades have passed any particular abutment, communicate with the space between such abutment and the next succeeding one and permit the steam in such space to exhaust out through the channels G and thence through ports G' into a hollow shaft section F' on the opposite side of the piston from the central opening C' and be supplied thence in any suitable manner to a secondary engine when the engines are compounded.

In forming the ports C^3 which operate either as feed or relief ports according to the direction in which the engine is run, we prefer to make them in the piston blades D' , the latter having their central portions D^2 dovetailed into connection with the piston body as shown in Fig. 3, and made of such length that it will operate in the slot or space A^9 in the casing, and this central portion of the piston blade has a chamber D^3 registering with the steam passage C^2 and receiving steam therefrom. The valves H operate in their respective chambers D^3 and are provided with feed passages H' and relief passages H^2 . The relief passage H^2 is diametrically opposite the feed passage H' , and the valve H is made cylindrical so it can turn in its chamber D^3 , and is also movable longitudinally in the said chamber. In addition to the ports G , we provide the piston with what for convenience of reference we term relief ports C^3 leading to relief channels G^2 which communicate with the exhaust ports G' , are provided with check valves G^3 , and serve as reliefs for any steam, condensation, or the like, that may accumulate in advance of the piston blades. As shown in Fig. 3, it being understood that the piston is moving in the direction indicated by the arrows in said figure, the relief passage H^2 will maintain communication between relief channel G^2 and the steam space C^4 so that as the piston advances, any

steam or the like in advance thereof may be relieved through the said ports and the channels G^2 . In such position of the parts, it will be noticed that the valve H has its channel H' communicating at one end at H^3 with the ports C^3 , and at its other end H^4 with the feed channel C^2 , and the intermediate imperforate portion H^5 of the valve between the ports H^3 and H^4 closes the relief port on such side of the valve. It will also be noticed that this imperforate portion H^5 is of sufficient length to maintain a cover for the idle relief port C^3 throughout a considerable adjustment longitudinally of the valve, which longitudinal adjustment of the valve is for the purpose of controlling the feed of steam to operate the engine by the adjustment of the valve by centrifugal action in order that the valve may be adjusted in accordance with the speed of the engine. This longitudinal adjustment of the valve is accomplished by means presently described, and we also provide for reversing the engine by turning the valves a half revolution, by the means presently described, so the engine may be driven in one direction or the other as desired. It will be understood that the valves will move outwardly by centrifugal action, as they slide radially within their chambers D^3 . In controlling this radial movement of the valves, we extend their stems H^6 inwardly within the feed channel C^2 toward the center of the piston, and provide them near their inner ends with grooves H^7 entered by forks on one of the arms of bell crank levers H^8 , the other arms of said levers being arranged to enter grooves in a collar H^9 , sliding on an adjusting shaft I operating within the hollow shaft F , as best shown in Fig. 1. This adjusting shaft is movable rotarily within the hollow shaft F when so desired, but normally rotates with the said shaft in the operation of the invention. The collar H^9 is movable along the shaft I by means of a pin H^{10} projecting from a controlling rod H^{11} which extends longitudinally within the adjusting shaft I and is movable longitudinally therein and turns with the said shaft I , the pin H^{10} fitting in a longitudinal slot in the shaft I so the controlling rod H^{11} may be moved longitudinally with its pin H^{10} . The controlling rod H^{11} extends outwardly beyond the end of the shaft I , and is provided with a spring H^{12} and a nut H^{13} which may be adjusted to vary the tension of the spring, and thus control the operation of the valves by centrifugal action in the use of the invention. By this construction it will be noticed if desired an operator may push upon the outer end of the controlling rod to move the valves outwardly and thus slow down the engine, and the said rod may be adjusted to control the operation of the valves to any desired extent.

65 We provide for reversing the engine by

giving the valves a half rotation by the operation of the shaft I , through gearing, whereby the rotation of the shaft I relatively to the hollow shaft F will turn the valves a half revolution, and thus shift the valve from the position shown in Fig. 3 for instance, to a position the reverse of that shown in said figure, so that the engine will be driven in the opposite direction. To this end we provide the adjusting shaft I with a gear wheel I' meshing with pinions I^2 on the valve stems H^6 , so that the proper movement of the shaft I relatively to the shaft F , will adjust the valves H rotarily as desired. For turning the shaft I , we provide the collar J shown in Fig. 2. This collar has a worm wheel J' , meshing with a worm J^2 on the adjusting shaft I , and the collar J turns with the hollow shaft F , being provided with forwardly projecting arms J^3 , which project between correspondingly spaced apart arms in connection with the hollow shaft F , so that while the collar J turns with the shaft F , it is movable axially independent of the said shaft F . This construction by the meshing of the worm wheel with the worm on the adjusting rod, permits us to turn the shaft I relatively to the shaft F , by the movement of the reversing collar in an axial direction, which is accomplished in the construction shown by means of a lever K pivoted at K' at its lower end and having the grooved collar J revolving in a suitable bearing at K^2 . Thus in operation, the engineer may by shifting the collar J in one direction or the other, adjust the valves as may be desired to turn the engine in one direction or the other. The shaft I is held from moving longitudinally to the left, see Fig. 1, by a shoulder I^{10} which may be integral therewith or may be a collar suitably secured on the shaft as found convenient. The shaft is held from moving in the other direction by the gear wheel I' , which is keyed to the adjusting shaft and fits closely to the projection I^{10} shown in Fig. 16, which acts as a bearing for the hub of the pinions I^2 , which pinions are entered from the end and held in position by the hub of the gear wheel I' . These pinions I^2 have a slot in their central opening in which the stems H^6 enter, the stems being tongued to fit in the grooves in the pinions I^2 , causing the stems H^6 to turn with said pinions and also permitting the free centrifugal action of the stems H^6 , which governs the speed of the engine. The steam is supplied to the hollow shaft F from a feed pipe L through a bearing case L' , in which the hollow shaft F turns, the shaft F having a series of openings F^2 , through which the steam passes into the shaft F , and a feed band L^2 being arranged within the feed case and extending around the hollow shaft F and having an annular groove L^3 in its outer face for the passage of steam around the feed band, and perforations

L⁴ leading from the bottom of said groove and communicating with the feed openings F² so the steam may be supplied uniformly around the hollow shaft, and thus distributed thereto in an even manner as desired.

In the operation of our invention, it will be noticed that the valves will operate automatically to regulate the speed of the engine, by cutting off more or less steam by centrifugal action according to the speed of the engine, and that we may in practice conduct the exhaust from the primary engine to a secondary engine without the exhaust operating with more than the minimum back 10 action on any of the piston blades of the primary or preceding engine; also, that provision is made for relieving any pressure that may be in advance of any of the piston blades, when not compounding, and the 20 valves may be given a half revolution by means under the control of the operator in order to reverse the engine as desired.

It will be noticed that when the engine is revolving in one direction, it will operate to exert a considerable tendency in one direction upon the casing, and thus upon the foundation, and to overcome this we provide for exerting a corresponding tendency in the reverse direction upon the foundation, 25 by the transmission devices shown in Figs. 1 and 11, and which we will now describe. These comprise a case M bolted to the foundation and having a rim M' provided with an internal gear M² which is meshed by pinions M³ journaled to a disk M⁴ keyed upon the piston shaft so the disk M⁴ will turn with the piston shaft, and the pinions M³ will be caused to revolve by their meshing with the internal gear M² of the case M. These pinions M³ mesh at their inner sides with a pinion N' on a driven shaft N, which is arranged in alinement with the piston shaft, and is caused to turn by the meshing therewith of the pinions M³. These pinions M³ it 30 will be noticed exert a tendency on the transmission case in the reverse circumferential direction to the tendency exerted on the case A by the operation of the piston therein so that the opposing tendencies 35 counteract each other, and the strain upon the foundation is reduced until it amounts to practically nothing and the engine may be operated without exerting any appreciable strain upon its foundation. It will be understood that another object of the transmission gear is to gain speed in the driven shaft N. As will be understood from Fig. 11, the driven shaft will make five revolutions to one revolution of the engine.

60 The construction of the piston with its blades in connection with the sectional construction of the casing with the side sections having the inwardly projecting flanges, results in a piston having a body portion comparatively thin, and blades at the outer edge

of said body portion and extending laterally to the opposite sides thereof and operating between the inner and outer flanges of the side sections of the casing, whereby we secure a broad blade surface upon which the 70 steam operates with a comparatively slight side pressure on the cylinder or casing.

It will be understood that while we prefer to bolt the casing to a foundation, and to provide for revolving the piston, such operation 75 might be reversed and the piston be held from turning and the casing be arranged to turn on the piston, and in the latter event the casing might form a band pulley which will be found useful in economizing space. 80

We claim:

1. A rotary engine comprising a casing having the opposite side sections provided with the inner and outer flanges projecting toward each other, the inner flanges being 85 shorter than the outer flanges, forming between their adjacent edges an annular space for the body of the piston, and the inner faces of the outer flanges being recessed at intervals for the reception of the abutments, the 90 abutments operating in said recesses, a hollow shaft, a piston having a body secured to said shaft, and provided with piston blades and with steam channels leading thereto and communicating at their inner ends with the 95 hollow shaft, and having at their outer ends ports for the passage of steam to the steam space of the engine, valves movable longitudinally and rotarily in the piston and having ports controlling the passage of steam to the 100 steam space and also having stems extending inwardly toward the center of the piston and provided with beveled pinions, an adjusting shaft having a beveled gear meshing with the pinions of the valve stems, and turning normally with the hollow shaft, means for turning the said adjusting shaft relatively to the hollow shaft, whereby to rotate the valves, a controlling rod, operating longitudinally within the adjusting shaft, and intermediate 110 devices between such controlling rod and the valve stems, whereby the said rod may be operated to effect a longitudinal movement of the valve, all substantially as and for the purposes set forth. 115

2. A rotary engine comprising a casing, having the opposite side sections provided with inner and outer flanges, projecting toward each other, and forming a steam space, a piston having a body portion operating between the adjacent edges of the inner flanges, and laterally extending blades operating in the steam space of the engine the body portion of the piston being also provided with feed channels for the passage of steam to the 120 steam space, and means for controlling the passage of steam to the steam space, substantially as set forth.

3. In a rotary engine, the combination of a piston having a body portion and blades at 130

the outer edge thereof and extending laterally to opposite sides of the piston body, and a casing having a steam space receiving said laterally projecting blades, the body portion 5 of the piston being also provided with feed channels for the passage of steam to the steam space.

4. The combination of a piston having a body portion provided with feed channels for 10 the passage of steam, valves controlling such passage of steam, and laterally projecting blades at the outer edge of the piston body, cam plates revolving with the piston, a casing having a steam space for the operation of 15 the piston blades and provided with radially movable abutments, and intermediate connections between said abutments and the cam plates whereby the latter may operate the abutment relatively to the piston blades.

20 5. A rotary engine, having a piston comprising a body portion, having feed channels, blades at the outer edge of the body portion, and having valve chambers communicating with the feed channels, and ports leading 25 from said valve chambers, valves movable longitudinally and rotarily in the said valve chambers, means for moving the valves longitudinally, and means for moving the valves rotarily, substantially as and for the purposes 30 set forth.

6. A rotary engine, comprising a hollow shaft piston thereon having a body portion provided with feed channels for the passage of steam, and laterally projecting blades at 35 the outer edge thereof, and a casing having an inner circumferential portion underlying the piston blades, and having a circumferential channel for the reception of the piston body, and also provided with an outer circumferential wall, and with recesses therein 40 for the operation of abutments, a steam space being provided between said inner and outer circumferential walls of the casing, valves controlling the passage of steam through the 45 feed channels of the piston body, and means in the hollow shaft for operating the valves, substantially as set forth.

7. A rotary engine having a hollow shaft, a piston secured thereto and having steam 50 channels communicating with the hollow shaft, blades at the outer edge of the piston, and having valve chambers in communication with the steam channels, and provided with ports, valves in the valve chambers, 55 and ported to coöperate with the ports thereof, and movable longitudinally and rotarily in their chambers and provided with inwardly projecting stems, and means projecting within the hollow shaft, whereby to 60 control the longitudinal and rotary movements of the valves, substantially as set forth.

8. The combination of a hollow shaft, a piston having a body secured to said shaft, and provided with steam channels in communication with the bore thereof, piston

blades at the outer edge of the body, valves movable longitudinally and rotarily in the piston for controlling the feed of steam, means projecting within the hollow shaft for controlling the longitudinal and rotary 70 movements of the valves, a casing having a steam space for the operation of the piston blades, and also provided with recesses and abutments movable therein, cam plates secured to and revolving with the hollow shaft, 75 whereby they move in unison with the piston, and intermediate devices between said cam plates and the abutments in the casing, whereby the same are operated relatively to the piston blades, substantially as set forth. 80

9. The combination of a casing, a piston, valves controlling the passage of steam for operating the piston, and movable longitudinally and rotarily in the piston, and means whereby the said valves may be moved longitudinally and turned, substantially as set forth. 85

10. The combination of a casing having inner and outer circumferential walls, spaced apart forming a steam space, and the inner circumferential wall being provided centrally 90 with an annular opening for the reception of a piston body, a piston body operating in said annular opening, midway between the sides of the steam space and having piston blades 95 extending transversely across the steam space and also provided with feed channels for the passage of steam, valves controlling such passage of steam and movable longitudinally and rotarily in the piston, and 100 abutments in the casing, and means for operating the same.

11. The combination of a casing having inner and outer circumferential walls and having the inner wall provided centrally 105 with an annular opening for the reception of a piston body, a piston body operating in said opening, and having blades at its outer edge overlying the inner circumferential wall of the casing, and abutments operating in the 110 casing and provided with central packing portions overlying the joint between the body of the piston and the casing, substantially as set forth.

12. The combination of the casing having 115 a body portion provided with bearings and having at its outer end a widened portion forming lateral offsets and provided in the widened portion with a steam passage and with abutments, a shaft, cam plates on the 120 shaft and operating within the lateral offsets of the casing, connections between the cam plates and the abutments in the casing, a piston secured to the shaft and having blades operating within the steam space of the casing, and means for controlling the passage of steam to and from the steam space, substantially 125 as set forth.

13. The combination of the casing, a piston operating therein, abutments operating 130

within the casing, a shaft to which the piston is fixed, cam plates fixed on the shaft outside of and on opposite sides of the casing whereby they turn with the piston, and rods connected with the opposite ends of the abutments and extending thence through the casing and arranged for operation by the cam plates, substantially as set forth.

14. The combination of the casing, the piston operating therein, the valves operating in the piston and movable in an axial direction and also rotarily, a hollow shaft to which the piston is secured, valve stems projecting at their inner ends toward the center of the piston, beveled pinions on said stems, an adjusting shaft having a gear, meshing with said beveled pinions, bell crank levers having arms for operating the valve stems longitudinally, said levers being pivoted to the hollow shaft and having arms projecting toward the adjusting shaft, a collar on the adjusting shaft and grooved for the reception of said arms of the bell crank levers, a pin projecting through the adjusting shaft and engaged with said collar and a controlling rod slidable within the adjusting shaft and connected with the said pin for operating the same, substantially as set forth.

15. The combination of a shaft, a piston thereon, cam plates on the shaft on opposite sides of the piston and spaced apart therefrom and revolving with the shaft, a casing between the cam plates and having at its outer end lateral extensions overlying the cam plates, the piston being provided with blades operating in the casing and projecting into the portions thereof which overlie the cam plates, abutments operating in the casing and extending into the overlying portions thereof, and intermediate connections between the abutments and the cam plates, said connections extending through the inner side of the overlying portions of the casing, substantially as set forth.

16. In a rotary engine a casing having a steam space and a plurality of abutments movable across the same a hollow shaft, a piston operating in the casing and having blades, valves controlling the passage of steam to the steam space, the casing having three abutments for each blade of the piston and having exhaust channels intermediate the pistons and devices in the hollow shaft for operating the controlling valve, substantially as and for the purpose set forth.

17. The combination with a casing having a steam space and abutments movable across the same, of a piston operating within the casing and having blades arranged in such relation to the abutments of the casing that after the piston has passed any given abutment the steam space between the same and the next abutment to the rear will be unobstructed by piston blades, and longitudinally and rotarily movable valves in the piston

for controlling the passage of steam to the piston blades, the piston having an exhaust port in position to register with said unobstructed steam space, and means for relieving the pressure in advance of the piston, substantially as set forth.

18. The combination in a rotary engine with the piston having a valve chamber and relief and feed ports communicating therewith, of a valve operating in said chamber and movable longitudinally and rotarily therein and provided in one side with an exhaust port to communicate with the feed and relief ports of the chamber and having at its opposite side ports spaced apart, the inner port being adapted to receive the steam and the outer port to communicate with the feed port of the chamber, the valve having an imperforate portion between its inner and outer ports to close the relief port on the feed side of the valve, and means for operating the said valve, substantially as set forth.

19. The combination with a casing, of a piston operating therein, a valve in the piston and movable revolvably therein, a hollow shaft supporting the piston, an adjusting shaft turning normally with the hollow shaft and also capable of turning independently of the hollow shaft, means whereby the turning of the adjusting shaft may reverse the piston valves, the said adjusting shaft having a worm, a collar on the worm, intermediate devices between the collar and the hollow shaft whereby the collar will be turned with the hollow shaft but may be moved axially along the hollow shaft whereby to turn the adjusting shaft in the hollow shaft, and means for moving the said collar in an axial direction, substantially as set forth.

20. The combination in a rotary engine of a casing, a piston operating therein and having valves, a hollow shaft supporting the piston, an adjusting shaft within the hollow shaft, intermediate devices whereby the turning of the adjusting shaft may reverse the piston valves, a worm on the adjusting shaft, a collar having a worm meshing with that of the adjusting shaft, said collar being keyed to and movable longitudinally with relation to the hollow shaft, and means for moving said collar axially, substantially as set forth.

21. A rotary engine comprising a casing having a steam space, abutments movable radially across the same, and arranged in a series of six equidistant from each other, means for moving said abutments radially across the steam space, a piston within the casing and having two diametrically opposite blades operating in the steam space of the casing, the piston being provided between its blades with exhaust channels in rear of their respective blades in such relation thereto that they will after the piston blades have passed any particular abut-

ment communicate with the space between said abutment and the next succeeding one and also having in advance of said exhaust channels relief ports which communicate 5 with the exhaust ports and are provided with check valves, substantially as and for the purposes set forth.

22. The combination in a rotary engine with the casing and the piston of a hollow shaft connected with the piston, a bearing in 10 which said shaft turns and having a case and a steam band within the case and provided on its outer side with an annular groove and having ports leading therefrom, the hollow shaft being provided with openings with 15 which said ports communicate, substantially as set forth.

23. The combination in a rotary engine, of a casing having abutments, a hollow shaft, a

piston secured to the hollow shaft, and having blades operating in the casing, valves in 20 the piston and movable longitudinally and rotarly, an adjusting shaft extending within the hollow shaft, and turning with and independently of the said shaft, a driven rod ex- 25 tending within the adjusting shaft, and movable longitudinally therein, means for turning the adjusting shaft independently of the hollow shaft, intermediate gearing between 30 the adjusting shaft and the valve, and intermediate devices between the driven rod and the valves, substantially as set forth.
